ENGINE OPERATED PUMP

Filed June 17, 1929

UNITED STATES PATENT OFFICE

FRED G. SCHWEISTHAL, OF CHICAGO, ILLINOIS, ASSIGNOR TO STEWART-WARNER CORPORATION, OF CHICAGO, ILLINOIS, A CORPORATION OF VIRGINIA

ENGINE-OPERATED PUMP

Application filed June 17, 1929. Serial No. 371,681.

This invention has to do with engine-operated pumps for supplying the engine with liquid required for any function of the engine as fuel, lubricant, or cooling water, or any auxiliary or collateral pumping surface, and its purpose is to provide a casing for coupling the pump casing to the engine casing having extended into it in co-operating relation an engine member from which power for pumping is derived and a pump member through which that power is communicated to the pump. It consists in the elements and features of construction shown and described as indicated in the claims.

15 In the drawing:

Figure 1 is a partly sectional view showing the pump in top plan and the coupling casing and adjacent part of the engine casing in horizontal section at the plane of the axis of the engine cam shaft.

Figure 2 is a section at the line 2—2 on Figure 1.

Figure 3 is an end elevation of the coupling casing looking at the end which is mounted against the engine casing.

Figure 4 is a section at the line 4—4 on Figure 3.

Figure 5 is a section at the line 5—5 on Figure 3.

Figure 6 is a detail side elevation of the pump looking at the side at which the coupling casing is mounted against the pump casing.

Referring to the drawing:—A represents the engine casing; B represents the pump casing; C represents the coupling casing.

The engine casing has an aperture, 20, through which protrudes the engine shaft, 30, from which the power is to be derived for operating the pump. The pump casing has an opening, 40, into which protrudes the operating arm, 44, of the pumping member of the pump, said pumping member and the further details of the pump not being shown, and it may be understood that these details are of any suitable form and construction adapted for the particular purpose to which the pump is applied, as for pumping fuel, or for cooling water, or for any other auxiliary or collateral service.

The coupling casing, C, is formed for closing the aperture, 20, of the engine casing when the coupling casing is mounted against the engine casing in position permitting the engine shaft, 30, to protrude into the cavity of the coupling casing in proper position for co-operating as hereinafter described with the pumping member arm, 44. Before thus fitting and closing the aperture, 20, of the engine casing, the coupling casing is formed as to dimension and contour at the end which is mounted on the engine casing for protruding into and fitting said aperture, as seen at the inwardly protruding terminal, 21, of said casing, C, which is encompassed by a shoulder, 22, stopping exteriorly of the engine casing on the margin of the aperture, 20, and constituting the face of a flange, 23, having bolt holes, 23^a, through which bolts, 24, are inserted screwing into the engine casing for securing the coupling casing to the engine casing.

The cavity of the coupling casing is right-angled in extent comprising the portion, 25, through which the engine shaft, 30, extends, and in which there is provided a journal bearing, 26, for said shaft, and a portion, 28, extending at right angles to the first mentioned portion, 25, and opening through a face of said coupling at right angles to the plane of the shoulder, 22, at which the coupling casing is mounted on the engine casing as mentioned above, said face being adapted for seating the coupling casing, C, against the corresponding face, 41, of the pump casing formed at the end of the latter through which the pumping member arm, 44, protrudes, either of said parts,—coupling casing or pump casing,—being flanged encompassing said face for screws to be inserted through the flange and screwed into the other member. Preferably, as illustrated, the coupling casing has a flange shown at 29, and the pump casing has a flange shown at 43 for bolts, 44^a, inserted through the flange, 43, and screwing into the flange, 29, of the pump casing.

The engine shaft, 30, is provided at the end in the coupling casing with a cam, 34, and the pumping member arm, 44, is formed

for co-operating with the cam for deriving from the engine shaft positive movement in one direction for operating the pump, it being understood that the pump mechanism 5 comprises means for giving the pumping member its intake stroke and causing the terminal of the arm, 44, to follow the cam in the idle phase of the cam cycle. The cavity of the casing at the junction of the portions 10 through which respectively the engine shaft and the pumping member stem extend, is enlarged suitably for accommodating the co-operating action of the cam and the pumping member arm.

15 I claim:

1. In combination with an internal combustion engine having an aperture in its casing at which an essential operating member of the engine mounted for support within the 20 engine casing is exposed for communicating motion, a pumping apparatus comprising a pumper actuator, and a casing in which said actuator is mounted, said casing being formed with an aperture at which said actuator is exposed for being actuated, a coupling casing having a cavity extending through it from an opening in said casing at one side thereof to an opening at another side thereof, said casing being arranged to be secured to the 25 pump casing and to the engine casing with its said openings respectively mated to the openings of the pump casing and engine casing, said engine member and said pumper actuator, exposed at the engine casing and 30 pump casing apertures respectively being arranged for direct operative engagement with each other when the coupling casing is thus secured to the pump and engine casing.

2. In combination with an internal combustion engine having an aperture in its casing from which an essential operating member of the engine mounted for support within the engine casing is protruded for communicating motion, a pumping apparatus 40 comprising a pumper actuator, and a casing in which said actuator is mounted, said casing being formed with an aperture at which said actuator is exposed for being actuated, a coupling casing having a cavity extending 45 through it from an opening in said casing at one side thereof to an opening at another side thereof, said casing being arranged to be secured to the pump casing and to the engine casing with its said openings respectively mated to the openings of the pump 50 casing and engine casing, said engine member and said pumper actuator protruded at the engine casing and pump casing apertures respectively being arranged for direct operative engagement with each other when the coupling casing is thus secured to the pump 55 and engine casing.

3. In the construction defined in claim 2, the protruding engine member being a rotative shaft having a cam for actuating the 60

pump member, the coupling casing having at the side at which it is secured to the engine casing a cap portion for closing the engine casing aperture through which the said shaft protrudes, said cap portion of the coupling 70 casing having a journal bearing for the engine shaft antecedent to the cam thereon.

4. In the construction defined in claim 2, the protruding engine member being a rotative shaft having a cam for actuating the 75 pump member, the coupling casing having at the side at which it is secured to the engine casing a cap portion for closing the engine casing aperture through which the said shaft protrudes, said cap member of the coupling 80 casing having journal bearing for the engine shaft antecedent to the cam thereof and having oil ducts leading from the inner end of said coupling casing within the engine casing cavity to said shaft journal bearing for admitting lubricant from the engine casing to the shaft.

5. In the construction defined in claim 2, the protruding engine member being a rotative shaft having a cam for actuating the 90 pump member, the coupling casing having at the side at which it is secured to the engine casing a cap portion for closing the engine casing aperture through which the said shaft protrudes, said cap portion of the coupling 95 casing having a journal bearing for the engine shaft, with radial webs by which said journal bearing is carried in said cap portion of the coupling casing, and having a cavity leading from the inner end around said journal bearing past said radial webs to the locality of the co-operation of the cam and the pump-operating member, in which cavity said parts co-operate, whereby access 100 is afforded for lubricant from the engine casing to said cavity for lubricating said co-operating parts.

6. In the construction defined in claim 2, the protruding engine member being a rotative shaft having a cam for actuating the 110 pump member, the coupling casing having at the side at which it is secured to the engine casing a cap portion for closing the engine casing aperture through which the said shaft protrudes, said cap portion of the coupling 115 casing having a journal bearing for the engine shaft, and radial webs by which said journal bearing is carried in said cap portion of the coupling casing, and having a cavity leading from the inner end around said journal bearing past said radial webs to the locality of the co-operation of the cam and the pump-operating member, in which cavity said parts co-operate, whereby access 120 is afforded for lubricant from the engine casing to said cavity for lubricating said co-operating parts, the cap portion of the coupling casing which protrudes into the engine casing having a duct at the lower side leading 125 from the portion of said cavity in which 130

the cam and pumping member co-operate past the shaft journal bearing and opening within the engine casing, said duct being at the lower side of the shaft bearing, whereby 5 the lubricant obtaining access to the cavity for lubricating the cam and co-operating pumping member may drain back into the engine casing.

In testimony whereof, I have hereunto set 10 my hand at Chicago, Illinois, this 12 day of June, 1929.

FRED G. SCHWEISTHAL.
